COMBINATION SHOE POLISH BOTTLE AND APPLICATOR

Samuel W. Menefee, Jr., Manheim Township, Lancaster County, Pa., assignor to Corn Products Company, a corporation of New Jersey

Application September 20, 1957, Serial No. 47,797

Term of patent 14 years

(Cl. D58—8)

The dominant features of my design reside in the portions shown in full lines.

I claim:

The ornamental design for a combination shoe polish bottle and applicator, as shown and described.
